MULTIPLEX REPEATER

Walter J. Zenner, Des Plaines, Ill., assignor to
Teletype Corporation, Chicago, Ill., a corpora-
tion of Delaware

Application April 27, 1942, Serial No. 440,633

15 Claims. (Cl. 178—70)

This invention relates to telegraph systems and particularly to a multiplex repeater for storing telegraph signals for retransmission.

The principal object of this invention is the provision of a telegraph repeater system wherein message signal combinations are momentarily stored before retransmission.

Another object of this invention is to provide a telegraph repeater system which enables the transmission of signal messages from an incoming multiplex channel to an outgoing multiplex channel whereby marginal variations in speed of operation between the channels are automatically compensated.

This invention contemplates the use of a telegraph repeater mechanism comprising a set of five receiving relays actuatable from a receiving distributor connected to an incoming line in combination with a plurality of rotatable bails each one of which carries a set of five signal storage levers each settable by an according to signal conditions of a related receiving relay. After the lever of a particular bail are set up according to a signal code combination, the bail is released from a signal transferring position by energization of a magnet controlled by a local sixth pulse. The released bail is then rotated and enters a position whereat its levers selectively operate a set of contacts which are connected to a transmitting distributor which repeats the signal over an outgoing line. After the bail has thus performed its transmitting function, it is again released by a local sixth pulse and moves past a wipe-out comb which resets the displaced levers to their original positions.

Although the apparatus disclosed in the present invention may have various uses and applications for the storage and retransmission of telegraph signal code combinations, it has been designed for use particularly as a multiplex telegraph repeating apparatus. In the use of the repeater system shown herein connecting trunk lines are presumed to be operated at approximately the same speed though not necessarily at the same operating speed, having a maximum allowable speed variation which may vary between 97% and 103%. A transmitting source such as a tape transmitter will be used equipped with automatic devices to insert six blank signals per hundred operations into outgoing messages. When a channel operating at the minimum rate or 97% receives signals from a channel operating at the maximum rate or 103%, the repeater will suppress the six blank signals and solid copy will be retransmitted over the slower channel

without the loss of any intelligence signals. If both channels are operating at the same speeds, the entire six blanks will pass through the repeater. On the other hand, if an outgoing channel is operating at a greater speed than an incoming channel a sufficient number of blank signals are inserted into the outgoing line by the transmitting distributor to compensate for the variations in speed. Under this last condition the outgoing channel would repeat not only the original six blank signals but would also insert additional blank signals due to the particular type of variation in speed between the channels.

A more complete understanding of the present invention may be had by reference to the following detailed specification and the accompanying drawings wherein:

Fig. 1 is a front elevational view with portions broken away showing the signal storing mechanism embodied in the present invention;

Fig. 2 is an end view partly in section of the mechanism shown in Fig. 1;

Fig. 3 is a schematic wiring diagram illustrating one application of the present invention;

Fig. 4 is a perspective view of a portion of the blank signal suppressor mechanism embodied in the present invention.

Referring now particularly to Fig. 1 there is disclosed therein a storage and repeater mechanism which is adapted to be mounted between the frame members 10 and 11 which may be part of the framework of a telephone or telegraph exchange. A motor 12 carries a worm 13 mounted on its armature shaft 14 and through it drives the worm gear 15 attached to the shaft 16. A worm gear 17 on shaft 16 drives the gear 18 of shaft 19 which supports the rotary mechanism of the repeater.

The shaft 19 is journaled in bearings 22 and carries at one end a pair of spaced collars 23, 24, the latter of which is threaded on a bushing 25 integral with collar 23 which bushing carries a set of spacer washers 26 between which are journaled a plurality of bail supporting arm members 27. Similarly at the other end of shaft 19 there is disclosed a pair of collars 30 and 31 and a similar bushing (not sectionally shown) supporting a set of spacing washers 32 between which are journaled the bail supporting arm members 33. Each of the bail members 35, of which six are shown in the instant example, is thus rotatably supported at its extremities by arms journaled between the spacing washers 26 and 32.

55

Near the middle of the shaft 19, is mounted a friction clutch mechanism for controlling the rotation of the bail members 35. Fixedly attached to the shaft 19 is a collar 40 against which bears one end of a compression spring 41 whose other end presses against a collar 42 thereby causing a set of felt discs 43, a set of bail impellers 44, and a set of clutch driving discs 47 to be compressed between the collar 42 and the projecting collar 45 of a bushing 46. The felt discs 43, the bail supporting discs 44, and the metallic discs 47 are keyed for slideable movement on a sleeve 401. As shown in Fig. 2, the bail impellers 44 have slots 50 into which the bails 35 project. When shaft 19 is rotating any particular bail 35 which is not restrained from movement, will be rotated due to the frictional engagement of the felt discs 43 with the bail impellers 44.

A set of five relays 55 are attached (Fig. 2) to a transverse supporting plate 51. Each of the relays 55 has associated therewith an armature 65 pivoted at 62 and carrying at its end an adjustment screw 66. Extending between the frame members 10 and 11 is a channel member 68. In the channel member 68 there is slideably mounted a set of plunger 70 which align with the adjustment screws 66, Fig. 2, of the armatures 65. Each plunger has a reduction portion 71 extending through a spring 72 which normally urges the plunger downwardly as viewed in Fig. 1. The plunger extensions 73 align with and may be pushed against projections 74 of a set of latches 75 carried by the bails 35.

The latches 75 of which there are five mounted upon each bail are pivoted at 76 and urged in a clockwise direction as viewed in Fig. 1 by springs 77. The springs 77 extend between the lever members 78 and one end of the latch members 75. Normally, the levers 78 are held up by the latches 75 at the shoulder portion 79 due to the pulling action of the springs 77.

The bails 35 are held at their signal storing position by the armature 80 (Fig. 2) of a stop magnet 81, the projection 82 of the armature normally overlying in the path of the bail members 35. When the receiving distributor 83 shown in Fig. 3 operates to energize the selecting relays 55 according to the incoming signal code combinations the armatures 65 of the relays 55 are either retained in their original position or moved to the left in a clockwise direction as shown in Fig. 2 according to whether a marking or spacing impulse is received. If a marking impulse is received, armature 65 of relay 55 moves in a clockwise direction to move the armature screw 66 into contact with its plunger 70. This moves the plunger against the action of coil spring 72 into the projection 74 of the latch 75 rocking the latch 75 in a counterclockwise direction as viewed in Fig. 1, and permitting the lever 78 to move in a clockwise direction under the influence of spring 77. The levers 78 are either tripped or remain untripped depending upon the signal code combination received by the selecting magnets 55. After a code is received, the distributor 83 sends a local sixth impulse to the stop magnet 81, which upon its energization attracts its armature 80 in a clockwise direction as viewed in Fig. 2 against the force of the spring 831 to thereby remove the projecting edge 82 of the armature from the path of a particular bail 35. After this is accomplished the friction clutch members 44 carry the bail past the armature

80 in a counterclockwise direction as viewed in Fig. 2.

When because of the idleness of relays 81 or 84 their armatures 80 and 82 are permitted to remain de-energized for an extended period of time, storage bails in transit will accumulate behind the foremost ones of them that are intercepted by the respective armature projections 82 and 94. However, as between the projections 94 and 96 of armature 82, a minimum space will prevail, as designated in Fig. 2, with no intervening storage members 35.

Supported between the panel members 10 and 11 by means of the screws 85 and 86 is a bar 87 which carries a plurality of adjusting screws 88 which act as back stops for the armatures 65 of the selecting relays 55. Screw 85 connects strip 81 to the upper block member 58 while screw 86 connects the strip to the lower block member 59.

Mounted on the rear of the frame 10 is a bracket 90 which carries a further stop magnet 91 which acts to stop a bail in anticipation of its signal repeating position whereby to time its passage through the transmitting position. Associated with the stop magnet 91 is the armature 92 which is pivoted at 95 and normally urged to rotate in a counterclockwise direction by the spring 160. As the released bail moves in its counterclockwise direction, it encounters a first projection 94 of the armature 92 and is blocked from further movement until the relay 91 is energized. When relay 91 receives an impulse from the transmitting distributor 93 as shown in Fig. 3, the relay 91 is again energized and its armature 92 moves in a clockwise direction to free a particular bail 35 for further counterclockwise rotation. The bail 35 thus continues to rotate until it encounters a second projection 96 of the armature 92 where it is held in its transmitting position. As the bail is held in this position, a series of contact engaging levers 100 carried on plate 97 are thereby cammed counterclockwise about their pivot 101 against the action of their coil springs 102 or remain stationary correspondingly affecting the contacts 103 also mounted on plate 97. The brush 105 of a two-channel multiplex retransmitting distributor 93 rotates and sends the signal produced by the positions of the contacts 103 out over the line 105a and when the brushes 106 traverses the segments 107, a local circuit is completed to the stop magnet 91 to advance the bail 35 in its counterclockwise direction since the projection 96 is at this time moved out of the path of the bail 35 and in a counterclockwise direction upon the energization of the magnet 91. The projection 94 of the armature 92 then acts to time the entrance of a succeeding bail 35 into its transmitting position and the projection 96 of the armature 92 acts to retain such bail 35 in its transmitting position.

The mechanism for suppressing the blank signals which are transmitted over the incoming line 84 by some suitable means, for instance, by the instrumentality of a tape transmitter in which a number of blank signals are automatically sent, will now be described. In the present invention it is contemplated that six blank signals be sent over the line 84 with every 100 communication signals. A blank signal would accordingly be inserted in the message at approximately sixteen signal intervals. Attached to the vertically extending channel member 69 is a bracket 98 on which is suitably supported a rotatable shaft 110 which is supported at its other end by a bracket

111 attached to the frame member 10. The shaft 110 is held against longitudinal displacement by means of the collars 112 and 113, suitably mounted at the top and bottom of the shaft, respectively, by means of set screws. At points along the shaft 110 are fixedly mounted a series of lugs 115 (Fig. 4) having depending slotted portions 114 which straddle the reduced portions 73 of the armature setting pins 71 so as to be rotatable clockwise when any one of the shouldered pins is moved rightwardly by its armature 65, see also Fig. 2.

It is therefore apparent that if any one of the plungers 70 is moved to the left upon the energization of its associated magnet, rock shaft 110 will be rocked in a clockwise direction, as viewed in Fig. 2. At the upper end of the rock shaft is mounted a bell crank member 116 having an upwardly extending portion which is adapted to cooperate with a shoulder 117 of a lever 118 pivoted at 119 and urged in a counterclockwise direction by a spring 120. If one of the relays 55 becomes energized, its plunger 70 will rock the shaft in a clockwise direction and remove the shoulder 121 of lever 118 from behind the stop armature 80 which is associated with the stop magnet 81 so that the armature 80 is free to pivot out of the path of the bail and allow it to be released when the magnet 81 is energized. The upwardly extending portion of bell crank 116 latches behind shoulder 117 of lever 118 holding the rock shaft 110 in its clockwise position. However, if none of the plungers is actuated, the rock shaft remains in its original position and the shoulder 121 of arm 116 remains in the path of the armature 80 and prevents the energization of magnet 81 from releasing a bail 35.

When following the operation of any one of the relays 55, its plunger 70 rotates rock shaft 110 of the blank signal eliminating device and a ball 35 is released, it moves past the extremity of the lever 118, engaging it and pivoting the lever in a clockwise direction and thus allowing the rock shaft to rotate in a counterclockwise direction, inasmuch as the shoulder 117 of lever 118 is lifted out of the path of the upwardly extending portion of bell crank 116. The rock shaft 110 is biased in a counterclockwise direction by a spring 125 which is attached to a lug 126 depending from the rock shaft. When a blank signal is received by the receiving distributor 83 none of the relays 55 will be energized and the ball 35 is accordingly retained in its original position.

Accordingly, the signal storage bails 35 are restrained because the armature 80 of magnet 81 is not permitted to move to its attracted position and as a result, other bails 35 will accumulate behind the foremost one of them thus blocked, maintaining, however, a spaced relationship one from another of such distance that but one bail 35 may be permitted to escape the stop lug 82 of armature 80 coincident with the impulse operation of said armature when upon the receipt of a nonblank signal, the effect of energizing magnet 81 is not blocked by bell crank member 116. As the bails 35 receive their signal storage setting in accordance with the operation of the several setting relays 55, they pass in counterclockwise direction to accumulate behind the armature abutment 94 of the transmitting control magnet 91. Here again the storage bails 35 may be permitted to accumulate consistent with the speed of signal transmission as compared with the relay's frequency of magnet 91 which is deter-

mined, of course, by the frequency of operation of transmitting distributor 93.

When the ball 35 is released upon the energization of magnet 91 and the armature 82 is attracted withdrawing the projection 96, the particular ball 35 moves past the comb member 131 whose projections 130 engage any of the levers 78 which have been moved out of their unset position restoring such levers to their original positions ready for another signal.

As was previously mentioned in every 100 operations, six blank signals will be received over line 84 and the suppressing mechanism, therefore, will likewise function six times. If the transmitting distributor 93 is operating at the same rate of speed as the receiving distributor 83, it will send six blank signals over the line 105a. It is evident, of course, that the operation of controlling the contacts 103 will for any given signal, lag several signals behind the receipt of its corresponding line signal by the receiving distributor 83.

If the transmitting distributor 93 is operating at a slower rate of speed than the receiving distributor 83 by as much as 6%, the blank signals will not be retransmitted over line 105a inasmuch as the receiving distributor 93 is moving slower, and all of the signal code combinations set up on the bails 35 by the levers 78 will be used to transmit solid copy without the loss of any intelligence signals. However, if the transmitter distributor 93 is faster than the receiving distributor 83 it will insert a sufficient number of the additional blanks into line 105a to compensate for the difference in speed between the two distributors. It is assumed that all channels will be operated at substantially the same speed and will be allowed speed variations ranging between 97% and 103% as previously explained.

It will be understood that the speed of rotation of driving shaft 19 will be such that after a bail 35 encounters the first projection 94 of armature 92 and is stopped, it will be released to travel to the transmitting position blocked by the second projection 96 of the armature at the proper time interval for signal transmission.

Various modifications and changes may be made in the hereinbefore described invention without departing from the spirit and scope thereof. Although the invention has been described in connection with multiplex systems, it may also find uses and applications in other telegraph systems.

What is claimed is:

1. In a signal storage device, a set of receiving relays, means to condition said relays in accordance with incoming signals received over a line, a plurality of rotatable bails, a set of settable members carried by each of said bails, means controlled by the conditionment of said relays for permutably positioning said settable members in accordance with received signals, means to retain said bails in a position to store signal code combinations on said settable members and release said bail when a complete combination is registered for movement to a signal transfer position, means to time the entrance to and retain a released bail in a signal storage transfer position, and a set of transmitting contacts adapted to be permutably controlled according to the conditionment of said settable members for transmitting signal code combinations over an outgoing line.
2. In a multiplex system repeater, an incoming line over which blank signals are periodically

received along with message matter signals, a multiplex receiving distributor associated with said incoming line, a plurality of members, each carrying a set of signal storage elements and movable from a signal receiving position to a signal transfer position, a set of instrumentalities permutably conditionable by signals from said receiving distributor to selectively control said storage elements according to received signals, means normally operable to release one of said plurality of members from its signal receiving position after a message matter intelligence signal code combination is received, and means to render said last-mentioned means ineffective when a blank signal code combination is received.

3. In a signal storage device for association with an incoming line over which blank signals are received, a plurality of members each carrying a set of signal storage elements and movable from a signal receiving position to a signal communication position, means to condition said elements according to received permutation signals from said incoming line, means normally operative to retain said plurality of members in signal receiving position and to release said members for movement to its signal transfer position after a combination of intelligence signals is received, and means to render said release means ineffective when blank signals are received.

4. In a multiplex telegraph system, an incoming channel over which blank signals along with miscellaneous matter intelligence signals are periodically received, an outgoing channel susceptible of operating at a slower speed than said incoming channel within marginal speed limits of said incoming channel, a multiplex repeater interconnecting said incoming and outgoing channels, including a plurality of individually rotatable bails having thereon permutably conditionable elements to store the incoming signals prior to retransmission to the outgoing line, and a blank signal suppressor mechanism associated with said repeater including means for preventing rotation of said bails in response to blank signals and for permitting rotation of said bails in response to intelligence signals, said outgoing channel being thereby adapted to repeat all blank signals when said channels are operating at uniform speed and to send no blank signals when operating at its slowest tolerable limits of operation and to repeat a number of blank signals in its other tolerable operating speeds representative of the speed variations between the channels.

5. In a multiplex telegraph storage system, an incoming channel over which blank signals are periodically received, an outgoing channel, said channel being susceptible of operating within tolerable speed limits, means to insert blank signals into said incoming channel, a repeater interconnecting said channels, and a blank suppressor mechanism associated with said repeater including means for suppressing each of said received incoming blank signals and permitting the transfer of each intelligent signal code combination to said outgoing channel to thereby compensate for speed variations between said channels without the loss of intelligence code combinations.

6. In a signal storage device, an incoming line, a set of signal-responsive instrumentalities permutably conditionable by signals from said line, a plurality of members each carrying a set of storage levers and movable from a signal-receiving to a signal transfer position, a set of latches cooperating with said levers to normally hold said

levers in their unselected position, means associated with said instrumentalities for operating said latches to position said levers according to signal characteristics, means to successively release said members from their signal-receiving position to their signal transfer position after successive code combinations are received, a set of transmitting contacts at said signal transfer position adapted to be selectively operated according to the conditionment of said storage levers and an outgoing line associated with said transmitting contacts.

7. A multiplex repeater including a plurality of mechanical storage loops, each of which carries a set of storage elements for storing complete signal combinations, a multiplex receiving distributor, a plurality of relays conditioned by said multiplex receiving distributor, a multiplex sending distributor, a plurality of contacts which condition said multiplex sending distributor, and means for presenting successively each storage loop for selectively operating said signal storage elements to said plurality of relays to receive and store signal code combinations and means to thereafter release said storage loops to a position to cooperate with said plurality of contacts to transfer the stored signal code combinations to said multiplex sending distributor.

8. In a signal storage device, an incoming line, a plurality of members each carrying a set of signal storage elements and movable from a signal-receiving position to a signal transfer position, a set of signal-responsive instrumentalities for permutably conditioning said elements according to received signals from said line, means normally operative to successively retain each of said plurality of members in a signal-receiving position and to successively release each of said members for movement to its signal transfer position after a combination of intelligent signals is received, and means common to said signal-responsive instrumentalities and actuatable by any one thereof for preventing the release of said members unless at least one of said instrumentalities is actuated in a given code combination.

9. In a signal storage device, an incoming line, a set of signal-responsive instrumentalities permutably conditionable by signals from said line, a plurality of members each carrying a set of storage levers and movable from a signal-receiving to a signal-transfer position, a set of latches cooperating with said levers to normally hold said levers in their unselected position, means associated with said instrumentalities for operating said latches to position said levers according to signal characteristics, means to successively release said members from their signal-receiving positions to their signal-transfer positions after successive code combinations are received, a set of transmitting contacts at said signal-transfer position adapted to be selectively operated according to the conditionment of said storage levers, and a reset means having projecting members in the path of displaced levers for resetting said levers to their original positions, means to retain the release member in its signal-transfer position, and means to release said member to enable the displaced levers to engage said projections of said reset means to enable said levers to return to their original positions.

10. In a multiplex repeater, a signal line, a plurality of members each carrying a set of signal storage elements and movable from the signal-receiving position to a timing position and thence to a signal-transfer position, means to

permutably condition said elements according to signals received over said line, means operative to retain each of said plurality of members in its signal-receiving position and to successively release each of said members for movement to its timing position after a given combination of signals is received, means for temporarily retaining a release member in its timing position and releasing said member for further movement to a signal-transfer position, a set of signal receiving instrumentalities selectively operable by said storage elements, and means to maintain said member in its signal-transfer position to transfer a stored signal combination from said storage element to said instrumentalities and release said member after a stored signal is transferred.

11. In a signal storage device, an incoming line, a plurality of members each carrying a set of signal storage elements and movable from a signal-receiving position to a signal-transfer position, a set of relays for permutably conditioning said elements according to received signals from said incoming line, and means operative to successively retain each of said plurality of members in its signal-receiving position and to successively release each of said members for movement to its signal transfer position after a combination of signals is received.

12. In a system of permutation code signal retransmission, a plurality of signal storage members each having conditionable elements corresponding to the components of a permutation code, driving means for propelling said members over a circuitous course individually and successively, a magnet responsive to incoming signals having an armature for accumulating said members at a signal storage position in said course and for releasing each one of said members singly to be driven by said propelling means, a magnet located at a retransmission position in said course and responsive to local distributor impulses for releasing said storage members singly following the transfer of permutation code signals therefrom, and a series of retransmission

contact pairs located at said retransmission position in said course actuatable by said storage member elements when their storage member is disposed thereof.

- 5 13. In a multiplex transmission system, a multiplex receiving distributor, a multiplex retransmitting distributor, a plurality of signal storage members, means for individually advancing said signal storage members from a position associated with one of said distributors to the other over a circuitous course, a relay for arresting said members in signal storage position under the control of said multiplex receiving distributor, means for arresting said storage members in signal transmitting position under the control of said multiplex retransmitting distributor, and a conditioning apparatus for said receiving distributor arresting means to prevent its effectiveness in the event of certain classes of permutation code signals.
- 10 14. In a retransmitting apparatus for repeating signals over a multiplex system, a plurality of individually revoluble storage members driven over a circuitous course, electromagnetic means for collecting said members at a signal storage position under the control of a multiplex receiving distributor, electromagnetic means for collecting said members in signal retransmitting position under the control of a transmitting distributor, and signal wipe-out apparatus located with respect to said course to engage said members during their travel from said signal retransmitting position to said signal storage position.
- 15 15. In a metal storage transmitter, a frictionally driven apparatus for advancing a plurality of storage units from a signal receiving position to a signal retransmitting position, means responsive to the reception of a general class of permutation code signals for effecting the advancement of one of said storage units, and apparatus responsive to certain signal combinations only for preventing the effectiveness of said advancement effecting means.
